Primary Examiner — Susan Bennett Hattan*Assistant Examiner* — Omeed Agilee(74) *Attorney, Agent, or Firm* — Edward J. Baba; Bret E. Field; Bozicevic, Field & Francis LLP(57) **CLAIM**

The ornamental design for sample container, as shown and described.

DESCRIPTION

FIG. 1 is a first side view of a sample container;
 FIG. 2 is a second side view of the sample container;
 FIG. 3 is a third side view of the sample container;
 FIG. 4 is a fourth side view of the sample container;
 FIG. 5 is a top view of the sample container;
 FIG. 6 is a bottom view of the sample container;
 FIG. 7 is a bottom perspective view of the sample container;
 and,
 FIG. 8 is a top perspective view of the sample container ap.
